[57] CLAIM

The ornamental design for a trophy or similar article, as
shown and described.

DESCRIPTION

FIG. 1 is a front elevational view of a trophy or similar
article showing my new design;

FIG. 2 is a rear elevational view; and

FIG. 3 is a right side elevational view, the left side being
a mirror image.

The broken line showing of attachable scoring medallions
in FIGS. 1 and 3 is for illustrative purposes only
and forms no part of the claimed design.
